APPARATUS FOR STORING AND DISPENSING ARTICLES

John J. Horan, Snyder, and Otto Du Pernell,
Cheektowaga, N. Y.; said Du Pernell assignor
to said Horan

Application March 13, 1933, Serial No. 660,584

13 Claims. (Cl. 194—4)

This invention relates generally to the type of apparatus known as dispensing or vending machines, and it has particular relation to an apparatus designed to utilize a container as a medium for initiating actuation of a mechanism to dispense an article of merchandise in return for each container.

One object of the invention is to provide an apparatus suitable for receiving containers, such as bottles, and utilizing them as a medium for initiating the operation of a dispensing mechanism and automatically storing the containers after they have served their function of operating the dispensing mechanism.

Another object of the invention is to provide an apparatus suitable for receiving containers, such as bottles, and utilizing them to initiate the operation of a dispensing mechanism from which suitable articles are expelled and which operates automatically to bar insertion of further containers, as well as to stop operation of the dispensing mechanism, after the last article has been exhausted therefrom.

Another object of the invention is to provide an apparatus designed to receive containers, such as bottles, to be utilized in initiating the operation of a dispensing mechanism and including a construction so arranged that the actuating mechanism for operating the device may be moved independently without damaging the dispensing device even though the parts of the latter may be locked against movement.

Another object of the invention is to provide an apparatus suitable for receiving containers of a relatively fragile nature and automatically to arrange the containers in stacked relation from the bottom of the container to the top of a storage space without danger of damaging or breaking such containers.

In the drawings:

Fig. 1 is a perspective of an apparatus embodying the invention;

Fig. 2 is a fragmentary view partially in vertical section and partially in elevation of the apparatus shown in Fig. 1;

Fig. 3 is a fragmentary horizontal section on a larger scale taken substantially along the line 111—111 of Fig. 2;

Fig. 4 is a fragmentary horizontal section similar to Fig. 3, but illustrating the operating elements of the apparatus in a different position;

Fig. 5 is a fragmentary vertical section taken substantially along the line V—V of Fig. 3;

Fig. 6 is a fragmentary vertical section similar to Fig. 5, but from the other side of the apparatus

and showing operating elements of the apparatus in elevation:

Fig. 7 is a fragmentary perspective of a dispensing mechanism embodied in the apparatus;

Fig. 8 is a perspective of a cam support and article shifting member embodied in the structure; and

Fig. 9 is a plan of the structure shown in Fig. 1.

A practical embodiment of the invention is exemplified in a casing or cabinet 10 which can be constructed in any convenient configuration, and it has an opening 11 adjacent its upper extremity at such position as to be readily accessible to persons standing adjacent the casing. An upwardly opening closure 12 having a hinge 15 normally maintains the casing closed from the top by means of a lock 16. Wall portions of the casing defining the opening 11 of the casing are adapted to be rolled inwardly to form beaded portions 17 and 18 bordering the opening, and a suitable door 19 (Fig. 2), providing access to the interior of the casing, is normally maintained locked.

An actuating lever 20 having a knob 22 at its outer end extends through a slot 23 in the casing adjacent the opening 11 and comprises a lower actuating arm or handle 25, an upright pivotal rod section 26, and lateral cam actuating arms 27 and 28. One of the cam actuating arms 27 constitutes a rigid projection of the lever 20, whereas the other cam actuating arm 28 has its one end rotatably mounted upon the rod section 26 and its other end portion extending beyond the outer end of the rigid arm 27 to form a curved end portion 29. A suitable spring 30 having end connections 32 and 33 to adjacent ends of the rigid arm 27 and pivotal arm 28, respectively, provides for concurrent movement of the arms 27 and 28. Relative movement of these arms is resisted by the spring 30, and although, under certain conditions such relative movement is effected, it is possible only in opposition to the resiliency of the spring.

A supporting frame 35 having suitable connections 36 to the wall of the casing 10 is provided with spaced upper and lower sections 37 and 38 in which the upper and lower portions of the rod section 26 of the lever 20 are rotatably mounted, as indicated at 50 and 52, respectively. Suitable spacing washers 53 and 55 separate the arm 28 from the upper frame section 37 and the handle arm 25 from the lower frame section 38, respectively. Thus the lever 20 is rotatably mounted in the frame 35 about the axis of the upright rod section 26.

The outer end of the pivotal cam actuating arm 28 is provided with a pin 56 that is rigidly mounted thereon and is disposed in a cam slot 57 formed in a plate 58 that is rigidly mounted upon a rotatable cam support 60. One end of the pin 56 is provided with a head 62, and the plate 58 is confined between the end 29 of the arm and the head, thus preventing the pin from being displaced from the slot 57. As best shown in Fig. 8, the cam plate 58 is rigidly secured to an upper horizontal leg 63 of a U-shaped portion 65 of the cam support. This upper portion of the cam support has a horizontal extension 66 on the leg of the U-shaped portion terminating in a fork 67 and the lower horizontal leg 68 of the U-shaped portion is bent downwardly to form a vertical leg 69 having a laterally bent foot 70 formed thereon. Aligned openings 72 in the extension 66 and the foot 70, respectively, receive a vertical rod 73 which pivotally carries the cam support 60 and has its opposite end portions mounted, as indicated at 75, in the upper and lower frame sections 37 and 38.

A second plate 76 (Fig. 8) is mounted upon the leg 68 of the cam support and has plate sections 77 and 78 extending laterally therefrom. A cam slot 79 of curved configuration slidably receives a pin 80 (Figs. 3 and 4) that is rigidly mounted in the end portion of a lever arm 82 constituting a part of a closure actuator 83. An intermediate portion on the arm 82 is pivotally supported upon an upright rod 85 that has its opposite ends secured in the frame sections 37 and 38. An intermediate portion of the closure actuator is in the form of a vertical section 86 (Fig. 6) and is secured, as indicated at 87, to a vertical wall 88 of a closure 89 composed of sheet material. The closure actuator also has a lower arm 90 parallel to the upper arm 82 and is pivotally supported upon the lower end of the rod 85.

The closure 89 comprises a vertical outwardly curved wall portion 92 which closes the opening 11 in one position of the lever arm 82. The other wall portion 88 to which the arm 82 is secured is curved into substantially channel form and in a direction opposite the curvature of the wall portion 92. A slot 93 through which the extension 66 of the cam support 60 extends is sufficiently long to receive the extension in various relative positions of the cam support 60 and the closure 89. A second slot 95 in the wall portion 88 is adapted to provide for movement of the closure beyond an extended portion of a cam plate 96, the latter of which is rigidly mounted, as indicated at 97, upon the upper section 37 of the frame 35, and is further formed with an outer cam face 98.

A lever 99 mounted intermediate its ends upon a pivot 100 on the upper frame member 37, has a rounded end 102 adjacent the cam face 98, and a link 103 secured by means of a thumb screw 105 is supported adjacent its other end. The lever 99 is substantially Z-shaped (Fig. 5) and its intermediate section 106 extends downwardly to a position adjacent the lower frame member 38 where its lateral arm 107 is formed for receiving the thumb screw 105.

As best shown in Fig. 7, the end portion of the link 103 opposite the thumb screw is pivotally connected, as indicated at 108, to a slide 109 that is movable horizontally in a guide 110 of a dispensing or discharging device 112. Suitable flanges 113 on the guide engage opposite edges

of the slide, and the slide and guide have registering slots 115 and 116, respectively, formed therein. A forward edge portion 117 of the slide extends transversely across the guide, and the slots 115 are spaced slightly to the rear thereof. A platform 118 supported upon the lower frame section 38 carries the dispensing device 112 and the guide 110 is secured in superposed relation thereon. A laterally closed chute 120 extending integrally from, and at an incline to, the guide projects through a slot 122 in the wall of the casing 10 and terminates in a receptacle 123 accessible from outside the casing. A flange 125 of the platform is inclined downwardly to assist in supporting and positioning the dispensing device on the platform.

An upright magazine 126, having a pair of oppositely disposed slots 127 at its lower end facing the slide and chute, respectively, has a bracket or strap 128 secured thereto adjacent the upper frame member 37. This bracket is apertured to fit over a pin 129 in the frame member for detachably maintaining the frame and magazine in firmly assembled relation. A pair of lugs 130 formed on opposite sides of the magazine serve to position the latter by fitting into notches 132 in the upper ends of flange portions 133 extending upwardly and integrally from opposite sides of the guide 110. Access to the magazine for replenishing it with suitable packages or articles 135 of merchandise, or the like, stacked therein is had by opening the closure 12, lifting the magazine bodily from the casing, and removing a cover 136 fitting over the top thereof. The cover extends upwardly and constitutes an integral part of the bracket 128. A pair of fingers 137 formed upon the lower side of a follower 138 that is normally disposed upon the top of the stack of articles 135, are designed to fit into the registering slots 115 and 116 of the slide 109 and guide 110 to lock them against relative movement when the magazine is empty.

In the operation of the apparatus an article 139, such as a bottle is suspended by its neck in the fork 67, while the various operating elements are positioned, as illustrated in Fig. 3. Then the knob 22 of the operating lever 20 is moved in a counter-clockwise direction, as viewed in Figs. 3 and 4, about the pivotal rod section 26 and the pin 56 of the pivotal arm 28 moves the cam support 60 in a counter-clockwise direction to swing the extension 66 and fork 67 to the position shown in Fig. 4. The force exerted for causing the movement of the cam support 60 is transmitted through the spring 30. As the bottle is carried to the position shown in Fig. 4, it contacts the cam surface 98, and at the same time, contacts the rounded end portion 102 of the lever 99. By forcing the bottle against this cam surface it moves outwardly on the cam surface against the end of the lever 99 and actuates the latter in a counter-clockwise direction about the pivot support 100 and also forces the bottle from the fork 67.

In order to stack and store a number of bottles 139 progressively in the casing, alternately and oppositely disposed baffles 150 are arranged in staggered relation in the casing and are supported upon brackets 152 that are mounted upon the wall of the casing. Each baffle slopes slightly toward the central portion of the casing 10 toward the space between two oppositely disposed baffles. When a bottle is released from the fork 67, it drops upon the upper baffle in the position shown in Fig. 2 and rolls slowly from baffle to baffle until it reaches a lower sloping platform 153 that extends entirely across the lower portion of the casing and 150

is supported by brackets 155 secured in the casing in a conventional manner.

Pivotal movement of the lever 99 caused by the bottle moving thereagainst operates the slide 109 toward the slots 127 in the lower portion of the magazine. The lowermost article 135 of the stack in the magazine registers with the slots and as the forward edge 117 of the slide is forced through the slot the article is discharged or expelled from the magazine into the chute and slides or falls by gravity into the receptacle 123. The articles may be in the form of pieces of chewing gum, candy or the like, and are adapted to be dispensed in return for the bottle, such as a milk bottle.

In the movement of the cam support 60 in a counter-clockwise direction the pin 80 operating in the cam slot 79 causes the closure operating arm 82 to move the closure wall 92 to close the opening 11 and thereby prevent access to the interior of the casing. By returning the knob 22 in a clockwise direction to its original position all of the elements referred to resume their original position as shown in Fig. 3.

However, if the articles are exhausted from the magazine 126 the last article to be expelled from the magazine permits the follower 138 to fall by gravity upon the slide 109 and the fingers 137 drop through the registering slots 115 and 116 of the slide and guide, thereby locking them against relative movement. Then movement of the lever 29 is possible but only against the resistance offered by the spring 30 which is thus extended. However, the elements of the apparatus cannot be shifted to receive a bottle upon the fork 67 until the magazine has been removed and the fingers 137 withdrawn from the slot of the slide and guide. In removing the magazine the top closure 12 is opened and the upper and lower portions of the magazine detached from the pin 129 and notches 132, respectively, by lifting it. After refilling the magazine the parts of the device are again positioned as shown in Fig. 3 for repeating the operation as described.

While bottles and pieces of merchandise are shown and described as articles suitable to be received and dispensed in the apparatus, it is to be understood that various other kinds of objects can be employed by modifying the receiving parts to conform to the shape of the various objects.

Although only one form of the invention has been shown and described in detail it will be apparent to those skilled in the art that the invention is not so limited but that various changes may be made therein without departing from the spirit of the invention or from the scope of the appended claims.

We claim:

1. A vending apparatus comprising a primary actuating device, a pivotal arm for releasably supporting an article in movable relation from one position to another, means for pivotally supporting said device and arm, a connection spaced from said means for transmitting force from said device to said arm, a package discharging mechanism, a member operable by moving said article against said member in response to movement of the arm to actuate the package discharging mechanism, and means for releasing the article from the first mentioned means during the operation of said member.

2. A vending device comprising a primary actuating device, a pivotal arm for releasably supporting an article in movable relation from one position to another, means for pivotally supporting

said device and arm, a cam connection spaced from said means for transmitting force from said device to said arm, a package discharging mechanism, a member operable by moving said article against said member in response to movement of the arm to actuate the package discharging mechanism, and means for releasing the article from the article supporting arm during the operation of said member.

3. A vending apparatus comprising a primary actuating device, a pivotal arm for releasably supporting an article in movable relation from one position to another, means for pivotally supporting said device and arm, a projection and cam slot connecting said device and arm for transmitting force from the one to the other, a package discharging mechanism, a member operable by moving said article against said member to actuate the package discharging mechanism, means for releasing the article from said arm during the operation of said member, and means cooperating with gravity for guiding the released article along a predetermined path.

4. A storing and vending apparatus comprising a casing having an article receiving opening 100 therein, a support in the casing, an operating lever pivoted on the support, an arm movably mounted upon the support for releasably supporting an article in movable relation from one position to another, power transmitting means 105 connecting the lever and arm at a location spaced from their mounting on the support, a package discharging mechanism, a member operable by movement of said article against said member to actuate the package discharging mechanism in 110 response to movement of the arm, means for releasing the article from said arm during the operation of said member, and means responsive to the operation of said arm to close the casing opening.

5. A storing and vending apparatus comprising a casing having an article receiving opening therein, a support in the casing, an operating lever pivoted on the support, an arm movably mounted on the support for releasably supporting 120 an article in movable relation to transport it away from the casing opening, power transmitting means connecting the lever and arm at a location spaced from their mounting upon the support, a package discharging mechanism including a package containing magazine and including an expelling member operable against a package in the magazine to discharge it, an actuating member operable in response to movement of said article against said actuating member to 125 operate the package discharging mechanism, a closure for the casing opening, a closure operating member connected to the closure and movably mounted upon said support, means for connecting the closure operating member to the arm 130 to operate the closure upon operation of the arm, and means in the magazine for locking the package discharging mechanism against operation when the packages therein have been exhausted.

6. A storing and vending apparatus comprising a casing having an article receiving opening therein, a support in the casing, an operating lever pivoted on the support, an arm movably mounted upon the support for releasably supporting an article in movable relation to transport it inside the casing away from the opening, power transmitting means connecting the lever and arm at a location spaced from their mounting upon the support, a package discharging mechanism including a package containing mag-

- azine and including an expelling member operable against a package in the magazine to discharge it, an actuating member operable by moving said article against said member in response to actuation of the arm in moving the article, means responsive to movement of said arm for releasing the article from said arm during the operation of said actuating member, a casing closure movable into opening and closing relation to said casing opening, a closure actuator pivotally mounted upon the support and having a connection to the closure, a camming connection between said actuator and said arm whereby the actuator is responsive to the operation of said arm to open or close the casing closure.
7. In a vending apparatus, a casing having an opening therein for receiving an article, an article carrying device for releasably supporting an article in movable relation from one position to another in the casing, means for pivotally supporting said device, an operating member having a camming connection to said device, means for movably supporting said operating member, a closure structure for the casing opening, a camming connection between the closure structure and said device whereby the closure structure is responsive to movement of the device to open or close the casing opening, a package discharging mechanism, and means operable by movement of the article carried by the device into contact with said means to actuate said mechanism.
8. A vending apparatus comprising a primary lever, means for pivotally supporting the lever, mechanism for releasably supporting an article in movable relation from one position to another, yieldable means for transmitting force from the primary lever to said mechanism, a package discharging device, a member operable in response to an article being moved thereagainst by said mechanism to actuate the package discharging device, and means for releasing the article from said mechanism.
9. A vending machine comprising a primary lever, means for pivotally supporting the lever, mechanism for releasably supporting an article in movable relation with the mechanism, yieldable means for transmitting force from the primary lever to said mechanism, a package discharging device including a detachable package containing magazine, a member operable in response to an article being moved thereagainst by said mechanism to actuate the package discharging device, and means for releasing the article from said mechanism incidental to the operation of said mechanism.
10. A vending apparatus comprising a primary lever, means for pivotally supporting the lever, a pair of relatively movable arms included in one end portion of said lever, yieldable means for transmitting force from one arm to the other, mechanism for releasably supporting an article in movable relation from one position to another, means for connecting one of said arms to said mechanism whereby force is transmitted yieldably from said lever to said mechanism, a package discharging device, a member operable in response to an article being moved thereagainst by said mechanism to actuate the package discharging device, and means for releasing the article from said mechanism.
11. A vending apparatus comprising a primary lever, means for pivotally supporting the lever, mechanism for releasably supporting an article in movable relation from one position to another, resilient means for transmitting force from the primary lever to said mechanism; a package discharging device including a package containing magazine and including an expelling member operable against a package in the magazine to discharge it; an actuating member operable in response to an article being moved thereagainst by said mechanism to actuate the package discharging device, and means in the magazine for locking the package discharging device against operation when the packages are exhausted, said lever being yieldably movable against said resilient means while the locking means is in locked position but inoperative to effect operation of said mechanism.
12. A storing and vending apparatus comprising a casing having an article receiving opening therein, mechanism for releasably supporting an article in movable relation to transfer it away from the casing opening; a primary lever, means for pivotally supporting the lever, resilient means connected to the lever for transmitting force from the lever to said mechanism; a package discharging device including a package containing magazine and including a package expelling member operable against a package in the magazine to discharge it; an actuating member operable in response to an article being moved thereagainst by the article moving mechanism to actuate the package discharging device, a closure having connections to said mechanism and responsive to movement of the latter to close the casing opening, and means in the magazine for locking the package discharging device and casing closure when packages in said magazine are exhausted.
13. A vending apparatus comprising a primary lever, means for pivotally supporting the lever, a pair of arms constituting one end portion of the lever, one of said arms being rigid with the lever and the other arm being journaled thereon, a resilient connection between said arms, a cam support, means for pivotally supporting the cam support adjacent the lever, the journaled arm having a cam connection to the cam support for actuating the latter, a member included in said cam support for releasably supporting an article in movable relation, a package discharging device, an actuating element operable in response to an article being moved thereagainst by said member to actuate the package discharging device, and means for releasing the article from said member.
